[57] CLAIM

The ornamental design for a hair dryer, as shown and described.

DESCRIPTION

FIG. 1 is a right side elevational view showing my new design for a hair dryer, the left side being a mirror image of the side shown,

FIG. 2 is a rear view thereof,

FIG. 3 is a top front perspective view thereof,

FIG. 4 is a top rear perspective view thereof,

FIG. 5 is a bottom view thereof,

FIG. 6 is a front side perspective view thereof,

FIG. 7 is a right side elevational view, with the handle in a folded position; and,

FIG. 8 is a right side/bottom perspective view with the handle in the folded position.

The unshaded region of the front end forms no part of the claimed design.
